RELAY

Shirley L. Goldsborough, Basking Ridge, N. J.,
assignor to Westinghouse Electric Corporation,
East Pittsburgh, Pa., a corporation of Pennsylvania

Application August 1, 1944, Serial No. 547,561

5 Claims. (Cl. 175—294)

My present invention relates to a new protective relay for alternating-current lines, the principal novel characteristic feature of the relay being that it has a distance-response characteristic which can be readily and conveniently shifted or molded to fit different line-conditions.

This application is a continuation-in-part of my applications, Serial No. 504,695, filed October 2, 1943, for Long-line fault-detectors and relaying-systems, and Serial No. 513,356, filed December 8, 1943, for Modified-impedance carrier relays, with additional details relative to means for making three substantially independent adjustments on the relay, so that the user of the relay may readily and independently make any one of the three adjustments, without substantially disturbing either one of the others. A first adjustment-means enables the user to adjust the radius of the response-locus circle of the relay, when the locus of the line-impedance at the balance-point of the relay is plotted on rectangular coordinates of resistance and reactance. A second adjustment gives the user of the relay a choice as to the angle along which the center of the circle is displaced from the origin, thereby choosing the phase-angle at which the relay has preferential directional characteristics. A third adjustment enables the user to preselect the amount by which the circle-center is displaced from the origin along the preselected center-axis or angle, thus predetermining the amount of directional response which is superimposed upon an impedance-response. These three adjustments are preferably calibrated in ohms and angles, as the case may be.

Distance-type transmission-line relays, and reactance-relays, and combined impedance and reactance relays, or combined impedance and directional relays, have heretofore been used very successfully. It has been possible to design such relays, either on the balanced-beam principle or on various kinds of watt-response principles, so that any possible desired type of response-circle could be obtained with any possible circle-radius, and any possible position of the center of the circle. However, the relay-design has been a matter of calculation, or fixed predetermination, without the provision of means whereby the three above-mentioned circle-characteristics could be independently changed at will, changing any one of the characteristics without disturbing the setting of the relay as to the other two characteristics.

Many different types of directional distance relays have been known, with different combina-

tions of current and voltage on the operating-coil side and on the restraint-coil side of a balanced-beam relay, and in the two fluxes which are to be multiplied in an induction-disk relay, an induction-loop relay, or other type of wattmetric relay. Of all these types of current-voltage energizations of different kinds of directional impedance relays, however, there is only one, which I have thus far been able to discover, in which these three independent adjustments may readily be made, in a manner which can be precalibrated because each adjustment is substantially independent of either one of the other two adjustments.

15 A particular object of my invention, therefore, is to provide a beam-type relay having an operating coil which is responsive only to the line-current, and having a restraint-coil which is responsive to the vectorial sum of a line-voltage plus a function of a line-current, in conjunction 20 with adjustment-means for making the three substantially independent adjustments heretofore mentioned. By a beam-type relay, I mean to include any relay having an operating force 25 which is responsive to the square of any flux or field-strength, which I may call the operating-coil field-strength, and a restraining force which is responsive to the square of another flux or field-strength, which I may call the restraint-coil field-strength.

30 With the foregoing and other objects in view, my invention, as claimed in this application, consists in the circuits, systems, combinations, methods, apparatus, and parts, hereinafter described 35 and claimed, and illustrated in the accompanying drawing, wherein:

Figure 1 is an impedance-curve diagram, illustrative of my invention and of its application in transmission-line protection, and

40 Fig. 2 is a diagrammatic view of circuits and apparatus embodying my invention in an illustrative form of embodiment.

Fig. 1 is an impedance-diagram, in which I have shown some of the difficult conditions which 45 distance-type protective-relays must handle, particularly on the more heavily loaded and longer transmission lines, in which it is becoming increasingly difficult for the relays to distinguish between fault-conditions and load-conditions, or 50 to distinguish between momentary load-swings or synchronizing-surges from which the system has the ability to recover or stay in step, and those swings or surges which develop into a definite out-of-step condition. In Fig. 1, the apparent 55 line-impedance, or the quotient of line-voltage

divided by line-current, is plotted on rectangular coordinates representing the line-resistance R and the line-resistance jX .

In Fig. 1, it is easy to plot the fault-ohms, because the resistance-ohms and the reactance-ohms of the transmission-line are readily available. Thus, in Fig. 1, the line OE_cL_F is the line on which all of the impedance-ohms of the transmission-line will fall, and the point L_F represents the ohms for a solid fault at the far bus of the protected line-section. The vector L_{FR} represents the apparent impedance-value when the arc-resistance of a fault is included, or added to the impedance of the line-conductors. It is easy to plot these two impedance vectors L_F and L_{FR} .

It is generally much more difficult, however, to plot the impedance-values representing momentary load-swing and synchronizing-surges. Exact methods for accurately and laboriously calculating these swings and surges are known, and form no part of my present invention. An approximate idea of the manner in which the impedance-vector for a synchronizing-surge may shift can be gained by locating the point E_c , along the line L_F , which represents the distance, in ohms, of the electrical center of the transmission system, as measured from the relay-location. The surge-impedance vector, such as I_s in Fig. 1, will terminate approximately in a straight line $SS'-E_c-SS$ which is approximately at right angles to the fault-ohm vector L_F at the point E_c corresponding to the distance of the electrical center. The more severe the swing-condition, the closer this vector I_s will approach the fault-line L_F . Some particular maximum approach to the line L_F will represent the dividing-line between the ability of the system to stay in step, or to develop into a definite out-of-step condition. The particular vector I_s which is shown in Fig. 1 represents approximately the maximum position of the synchronizing-surge ohms from which the system can recover.

Generally, it is desirable to permit tripping for all surge-conditions from which the system cannot recover, that is, for surge-ohms terminating in the region E_cI_s in Fig. 1, but to prevent tripping for all load-conditions and surges up to this non-recovering point I_s . This means that the relay response-characteristic, when plotted on the $R-X$ diagram, as shown at $Z2$ in Fig. 1, must properly encircle the entire vector L_{FR} , representing line-fault ohms including fault-resistance, but it must not encircle the swing-ohms, in the region I_s-SS , from which recovery is possible.

In many or most transmission-lines, particularly the longer ones, the minimum synchronizing-surge ohms I_s for which it is not desired to have a relay-response, or a circuit-breaker tripping-action, may fall quite close to the fault-ohm line L_F . Moreover, each transmission-line is different, each having its own individual characteristic, and the characteristics may even change, particularly as to the position of the electrical center E_c of the system, during different system-conditions. My new relay is designed for the purpose of making it possible for the user of the relay to make calibrated adjustments of each one of the three characteristics which determine the size and the position of the impedance-circle, such as the circle $Z2$ in Fig. 1.

In Fig. 2, I have illustrated my invention as applied to the protective relaying of one phase of a three-phase transmission-line 3 , which is

connected to a three-phase bus 4 . The several phases, or phase-conductors, are distinguished by the letters A , B , and C . The relay is diagrammatically represented as a centrally pivoted beam 5 , shown in its non-energized position, or non-responsive position, having make-contacts 6 at one end. The front or contact-carrying end of the beam 5 is operated upon by a diagrammatically indicated operating-coil 7 , which develops an operating-force F_0 tending to close the relay-contacts 6 . The back end of the beam 5 is acted upon by one or more restraint-windings or coils, as diagrammatically indicated at 8 .

A relaying-current I is derived from the line 3 through line-current transformers 10 , and applied to the operating-coil 7 , and to the primary winding 11 of an auxiliary current-transformer 12 . A relaying-voltage E is derived from the line, by a potential-transformer 13 , and this voltage E is applied to the restraint-coil 8 through a voltage-shifter 14 . The auxiliary current-transformer 12 has a secondary winding 15 which feeds current into a current-type phase-shifter 16 of any suitable type, the same being illustrated as an inductance 17 , shunted by a resistance 18 , which is so connected as to add a current-responsive voltage-component to the voltage E in the energizing-circuit of the restraint-coil 8 , as will be subsequently described.

In the following derivations, we will regard lagging phase-angles as positive, and leading phase-angles as negative, so that lagging line-reactance X will be positive.

The operating-coil flux or field-strength may be written

$$H_0 = gI \angle (\theta + U) \quad (1)$$

and the restraint-coil field-strength may be written

$$H_r = hmI \angle (\theta + M) - hnE \angle N \quad (2)$$

where g , h , m , and n are any scalar-value constants; θ is the power-factor angle of the line, counted positive for lagging power-factors; U , M , and N are phase-shifter angles, counted positive for lagging phase-shifts; U is immaterial; N is the angle by which the voltage-responsive voltage-component applied to the restraint-coil 8 lags behind the line-derived voltage E ; and M is the angle by which the current-responsive voltage-component applied to the restraint-coil 8 lags behind the line-derived current I if I is in phase with E at unity power-factor, so that, in any event, regardless of the relative phases of I and E at unity power-factor, $(\theta + M)$ is the angle by which the current-responsive restraint-coil energizing-component lags behind the line-derived voltage E , taken as a reference-base.

The operating force of the relay is responsive to the square of the operating-coil flux H_0 . It is therefore

$$F_0 = g^2 I^2 \quad (3)$$

The restraining force of the relay is responsive to the square of the restraint-coil flux H_r . It is therefore

$$F_r = h^2 m^2 I^2 + h^2 n^2 E^2 - 2h^2 m n I E \cos (N - M - \theta) \quad (4)$$

The relay will operate when the restraining force F_r is less than the operating force F_0 , or when

$$h^2 m^2 I^2 + h^2 n^2 E^2 - 2h^2 m n I E \cos (N - M - \theta) < g^2 I^2 \quad (5)$$

If the operating and restraining forces had been proportional to the first power, rather than

the square, of the flux, the result would have been the same, using the square-root sign on each side of Equation 5, which could be instantly cleared by squaring both sides.

Dividing Equation 5 through by I^2 , and transposing one of the terms, and remembering that

$$\left. \begin{aligned} \left(\frac{E}{I}\right)^2 &= R^2 + X^2 \\ \frac{E}{I} \cos \theta &= R \\ \frac{E}{I} \sin \theta &= X \end{aligned} \right\} \quad (6)$$

and that

$$\cos(N-M-\theta) = \cos(N-M) - \cos \theta + \sin(N-M) \sin \theta$$

Equation 5 may be rewritten as

$$h^2 n^2 (R^2 + X^2) - 2h^2 m n R \cos(N-M) - 2h^2 m n X \sin(N-M) < g^2 - h^2 m^2 \quad (7)$$

If $h n > 0$, we may divide through by $h^2 n^2$ without changing the inequality-sign in Equation 7, obtaining an expression for the relay-response whenever

$$\left[R - \frac{m}{n} \cos(N-M) \right]^2 + \left[X - \frac{m}{n} \sin(N-M) \right]^2 < \frac{g^2}{h^2 n^2} \quad (8)$$

When the apparent line-resistance R and the apparent line-reactance X are plotted, as abscissas and ordinates, respectively, of a system of rectangular coordinates, the locus of the balance-point of the relay is thus a circle, as shown, for example, at Z2 in Fig. 1. If the relay is to operate, the apparent or measured line-impedance must fall inside of this circle.

The coordinates of the center C_0 of the circle, expressed in ohms, are

$$R_0 = \frac{m}{n} \cos(N-M) \quad (9)$$

$$X_0 = \frac{m}{n} \sin(N-M) \quad (10)$$

The radius of the circle, in ohms, is

$$Q_0 = \frac{g}{h n} \quad (11)$$

The slope or angle of the center-axis DD' , Fig. 1, or the line along which the center of the circle is displaced from the origin O of the resistance-reactance coordinates, is found from Equations 9 and 10, counting this angle positive when it leads the R -axis or lies in the first and third quadrants of the rectangular coordinates R and X (or beyond, if it is a larger angle). This angle is

$$S_0 = (N-M) \quad (12)$$

The displacement OC_0 of the center of the circle, measured in ohms from the origin along the line at the angle S_0 to the R -axis, is found from Equations 9 and 10 to be

$$D_0 = \frac{m}{n} \quad (13)$$

Examination of Equations 11, 12, and 13, for these three variations of the circle-characteristics, will show that the constants or controllable variables g and h occur only in Equation 11, the angle $(N-M)$ occurs only in Equation 12, and the

constant or controllable variable m occurs only in Equation 13. The variables g and h are the response-ratio factors dependent upon the effective number of turns and the effective magnetic reluctance (or airgap-setting) of the operating-coil 7 and the restraint-coil 8, respectively. Usually it is more convenient to vary only one of these factors g or h , usually h , and to calibrate the adjustment of the circle-radius Q_0 in ohms, as, for example, by turn-adjustment taps 19 on the operating-coil 7 of the relay, as shown in Fig. 2.

The angle, $-M$, is the angle by which the current-responsive voltage-component of the restraint-coil energization H_r leads the line-derived current I , if I is in phase with the line-derived voltage E at unity power-factor, the negative sign indicating that the angle is leading. If I is not in phase with E at unity power-factor, but lags it by some angle M_0 , as because of some star-delta transformation, then $(M-M_0)$ is the angle by which the current-responsive H_r component lags behind the line-derived current I . The angle N is the angle by which the voltage-responsive voltage-component of the restraint-coil energization H_r lags behind the line-derived voltage E . The angle $(N-M)$ is the angle by which the voltage-responsive H_r component lags behind the current-responsive H_r component at unity power-factor. At any power-factor angle θ , the voltage-responsive H_r component leads the current-responsive H_r component by an angle $(\theta+M-N)$.

In terms of the circle-diagram, plotted on $R-X$ coordinates, as shown in Fig. 1, the angle, $-M$, represents the angle D_60OR by which the current-responsive phase-shifter 16 causes the line DD' of circle-center displacement to shift, in a leading direction or counter-clockwise, with respect to abscissa-axis or R -axis; and the angle N represents the angle DOD_60 by which the voltage-responsive phase-shifter 14 causes said line DD' of circle-center displacement to shift, in a leading direction or counter-clockwise, with respect to the abscissa-axis of R -axis. The angle $(N-M)$ is the total angle S_0 between the line DD' of circle-center displacement and the R -axis. This total displacement-angle $S_0 = (N-M)$ of the response-circle can be varied, without varying either of the other circle-characteristics Q_0 or D_0 , by varying either N or M , or both, without varying the magnitude-ratios n or m . Usually it is more convenient to vary only the voltage-circuit phase-shifter 14 so as to change the angle N , and to suitably calibrate the adjustment in degrees.

A feature of my invention is to provide an adaptable impedance-circle relay in which the angle S_0 of the displacement of the circle-center C_0 from the origin O may be independently adjusted through any desired range, specifically through a range between 30° to the right or left of the ordinate-axis or the y -axis along which lagging line-reactances X are plotted. Thus, the angle $S_0 = (N-M)$ is varied, through a 60° range, from $S_0 = 60^\circ$ to $S_0 = 120^\circ$, leading with respect to the R -axis or abscissa-axis.

To this end, it is convenient to produce the non-variable 60° part D_60OR of the variable angle S_0 by the current-circuit phase-shifter 16, by assigning such values to the inductance 17 and the resistance 18 that the current in the resistance

18 leads the impressed current I by 60° , corresponding to $M = -60^\circ$. Any amount of the resistor-voltage of 18 is tapped off at 21, and connected in series between the voltage-source E and the restraint-coil 8, to provide the current-responsive component of the energization H_r .

Any suitable voltage-circuit phase-shifter 14 is then used, to shift the impressed voltage E by a variable amount from 0° to 60° in the lagging direction, corresponding to N= anywhere between 0° and 60°. Since the voltage-responsive component of the energizing-current in the restraint-coil 8 lags the impressed voltage by almost 90°, or by any convenient angle between say, 60° and 84°, I have shown a voltage-circuit phase-shifter 14 of a form invented by Herbert J. Carlin, as described and claimed in his application Serial No. 583,926, filed March 21, 1945, said phase-shifter comprising a mutual reactor 22 having a primary winding 23 which is connected in series with the restraint-coil 8, and a secondary winding 24 which is connected across the voltage-source E through a variable resistor 25, the value of which may be adjusted, as by a tap or taps 26, from open-circuit or infinity, down to a suitable amount, calibrated according to the corresponding phase-shift angle N, or calibrated according to the corresponding center-shifts slope

$$S_0 = (N - M)$$

in degrees, as the center-axis DD' is shifted between the limits D₆₀ and D₁₂₀ in Fig. 1.

This simple type of voltage-circuit phase-shifter 14 shifts the phase-angle N of the applied voltage without substantially varying the magnitude n of the response, and is quite sufficient where as much as a 5 or 10 percent variation (or other variation) in the radius R₀ and the displacement D₀ is within tolerable limits of accuracy. I wish it to be understood, however, that I am not limited to any specific kind of either current-type or voltage-type phase-shifter 16 or 14.

The constant or controllable variable m, which affects only the center-displacement D₀, without affecting either of the other circle-characteristics Q₀ or S₀, is a magnitude-ratio or response-ratio which is controlled by primary or secondary taps 27 on the restraint-energizing current-transformer 12, which may be calibrated directly in ohms of the displacement-distance D₀ between the circle-center C₀ (Fig. 1) and the origin O. Fine adjustments, for values between transformer-taps 27, may be provided by the resistor-taps 21 on the output of the current-circuit phase-shifter 16. When this current-transformer 12 is cut out of the current-circuit, the current-responsive restraint-component is zero, and the center C₀ of the circle is at the origin, corresponding to a pure impedance-response of the relay, without any directional discrimination.

If the circle is to pass through the origin, for a directional response, the center-displacement D₀ must equal the radius R₀, and Equations 11 and 13 show that, under such circumstances, the current-responsive operating-force g²I² must exactly equal the current-responsive restraint-force h²m²I² when the voltage-source E is unenergized. For larger displacements of the circle-center C₀ from the origin, hm must be larger than g. For smaller displacements, hm must be less than g, producing an impedance-characteristic with a sense of direction, so that the response to line-impedance is greater in some directions than others.

The center C₀ of the circle can thus be shifted up the slope-line DD' at the angle S₀ = (N - M), by increasing the current-responsive restraint-coefficient m, in any amount, which may be done by adjustment of the current-transformer taps 27, or the resistor-taps 21, or both. The circle-cen-

ter C₀ can be shifted in the opposite direction, or down from the origin, by reversing the polarity of either the current or the voltage on the restraint-side of the relay. None of these center-displacement adjustments has any effect upon either the radius R₀ of the circle or the angle S₀ along which its center C₀ is displaced.

In the particular embodiment shown in Fig. 2, I have shown a preferred choice of line-derived current I and line-derived current E, but I wish it to be understood that my invention is perfectly general, and my relay may be energized in response to any single-phase current I derived from the line, and any single-phase voltage E derived from the line, or voltage otherwise having the same frequency as the current. There is less difference in the response of the relay, between phase-to-phase faults and three-phase faults, if I use the delta line-current and the same phase 15 of delta line-voltage, defining the delta line-current as (I_A - I_B), or the difference between the line-current I_A in phase-A, and the line-current I_B in phase-B. The delta voltage E_{AB} is the voltage across the two line-conductors A and B. 20 However, other combinations of line-derived current and line-derived voltage may be utilized, provided that care is taken to make allowance for the phase-angle M₀ by which the derived current lags behind the derived voltage at unity-power-factor line-conditions, as previously explained.

In the foregoing explanation of my invention, I have designated the relay-coil 7 as an operating-coil which tends to close the make-contacts 6, and I have designated the other coil 8 as a restraint-coil. I have adopted this notation as a convenience of description, in accordance with the usual practice of having a distance-relay connected so that it remains in its non-energized position until the occurrence of the fault-conditions to which 25 the relay is designed to respond. I wish it to be understood, however, that my invention is obviously just as applicable to the type of relay which responds when there is no fault and which drops out during fault-conditions; in other words, 30 a relay having an ohm-characteristic rather than an impedance-characteristic, so that it responds to all impedance-values lying outside of the circle Z₂ in Fig. 1, and drops out for all impedance-values inside of said circle, instead of the other way around, as previously explained. Thus, if the force F₀ of Equation 3 were a restraining force rather than an operating force, and if the force F₀ of Equation 4 were an operating force rather than a restraining force, then the inequality signs 35 of Equations 5, 7, and 8 would be reversed, indicating an impedance-response for impedance-values outside of the circle, rather than inside of the same, and necessitating back-contacts rather than the make-contacts 6 of Fig. 2.

While I have indicated my invention in but a single form of embodiment, which I at present prefer, I wish it to be understood, therefore, that the previously outlined changes, and other departures, may be made in the exact details of embodiment without departing from the essential spirit of my invention, the broad idea of which is to provide a distance-type relay having a relay-characteristic which can be readily molded to best fit the conditions of any particular line, 60 and specifically having separate and independent adjustments for the diameter of the relay-circle, the slope of the displacement-angle of the relay-center, and the amount of displacement of the relay-center from the origin of the system 65 of R-X coordinates. I desire, therefore, that

the appended claims shall be accorded the broadest construction consistent with their language.

I claim as my invention:

1. An adjustable distance-type relay having an operating-circuit magnetizing-means, for producing an operating flux and an operating force responsive to the operating flux; a restraint-circuit magnetizing-means, for producing a restraining flux and a restraining force responsive to the restraining flux; energizing-circuit means, for energizing the operating-circuit magnetizing-means so as to be exclusively responsive to a line-derived current; two restraint-circuit energizing-circuit means for energizing the restraint-circuit magnetizing-means, one in response to a line-derived current and the other in response to a line-derived voltage; and means for making a substantially independent adjustment in each one of any pair selected from the three following constants, to wit: (1) the ratio of the response-ratios of the operating flux and the restraining flux, each of these response-ratios being dependent upon the effective number of flux-producing turns and the effective reluctance of the magnetic flux-path; (2) the angle between the voltage-responsive component of the restraining flux and the current-responsive component of the restraining flux at unity power-factor of the line; and (3) the response-ratio determining the magnitude of the current-responsive component of the restraining flux with reference to the line-derived current which produces it.

2. An adjustable distance-type relay having an operating-circuit magnetizing-means, for producing an operating flux and an operating force responsive to the operating flux; a restraint-circuit magnetizing-means, for producing a restraining flux and a restraining force responsive to the restraining flux; energizing-circuit means, for energizing the operating-circuit magnetizing-means so as to be exclusively responsive to a line-derived current; two restraint-circuit energizing-circuit means, for energizing the restraint-circuit magnetizing-means, one in response to a line-derived current and the other in response to a line-derived voltage; and means for making a substantially independent adjustment in each one of the two immediately following constants, to wit: (1) the ratio of the response-ratios of the operating flux and the restraining flux, each of these response-ratios being dependent upon the effective number of flux-producing turns and the effective reluctance of the magnetic flux path; and (2) the angle between the voltage-responsive component of the restraining flux and the current-responsive component of the restraining flux at unity power-factor of the line; each adjustment effecting substantially its own constant, without any substantial effect upon the other constant or upon (3) the response-ratio determining the magnitude of the current-responsive component of the restraining flux with reference to the line-derived current which produces it.

3. An adjustable distance-type relay having an operating-circuit magnetizing-means, for producing an operating flux and an operating force responsive to the operating flux; a restraint-circuit magnetizing-means, for producing a restraining flux and a restraining force responsive to the restraining flux; energizing-circuit means,

for energizing the operating-circuit magnetizing-means so as to be exclusively responsive to a line-derived current; two restraint-circuit energizing-circuit means, for energizing the restraint-circuit magnetizing-means, one in response to a line-derived current and the other in response to a line-derived voltage; and means for making a substantially independent adjustment in each one of the two immediately following constants, to wit: (1) the ratio of the response-ratios of the operating flux and the restraining flux, each of these response-ratios being dependent upon the effective number of flux-producing turns and the effective reluctance of the magnetic flux-path; and (2) the response-ratio determining the magnitude of the current-responsive component of the restraining flux with reference to the line-derived current which produces it; each adjustment affecting substantially its own constant, without any substantial effect upon the other constant or upon (3) the angle between the voltage-responsive component of the restraining flux and the current-responsive component of the restraining flux at unity power-factor of the line.

4. An adjustable distance-type relay having an operating-circuit magnetizing-means, for producing an operating flux and an operating force responsive to the operating flux; a restraint-circuit magnetizing-means, for producing a restraining flux and a restraining force responsive to the restraining flux; energizing-circuit means, for energizing the operating-circuit magnetizing-means so as to be exclusively responsive to a line-derived current; two restraint-circuit energizing-circuit means, for energizing the restraint-circuit magnetizing-means, one in response to a line-derived current and the other in response to a line-derived voltage; and means for making a substantially independent adjustment in each one of the three following constants, to wit: (1) the ratio of the response-ratios of the operating flux and the restraining flux, each of these response-ratios being dependent upon the effective number of flux-producing turns and the effective reluctance of the magnetic flux-path; (2) the angle between the voltage-responsive component of the restraining flux and the current-responsive component of the restraining flux at unity power-factor of the line; and (3) the response-ratio determining the magnitude of the current-responsive component of the restraining flux with reference to the line-derived current which produces it.

5. An adjustable directional impedance relay, comprising triply adjustable line-energized relay-means responding to a line-derived voltage and a line-derived current, for producing two separate relay-fluxes and a relay-response to line-impedance values lying within a response-circle, when the locus of all line-impedance values at the balance-point of the relay is plotted on rectangular coordinates of the line-resistance R and the line-reactance X , said line-energized relay-means having three separate adjustment-means, for separately and substantially independently adjusting each of the respective quantities, Q_0 , S_0 and D_0 , which determine said response-circle; where Q_0 is the radius of the circle, in ohms; S_0 is the slope of the center-axis of the circle; and D_0 is the displacement, in ohms, of the center of the circle from the origin.

SHIRLEY L. GOLDSBOROUGH.
